ELECTRIC HIGH PRESSURE DISCHARGE LAMPS

Wolfgang Emery Thouret, East Orange, N. J., assignor to Westinghouse Electric Corporation, East Pittsburgh, Pa., a corporation of Pennsylvania

Application January 21, 1953, Serial No. 332,481

1 Claim. (Cl. 315—47)

My invention relates to electric discharge lamps with solid incandescent electrodes, the electrode leads of which are connected by incandescent wires or incandescent coiled filaments parallel to the discharge path for the purpose of starting the discharge. Usually the wires or wire coils have such dimensions that they glow brightly when the mains voltage is switched on. They ionize the discharge path by emitted electrons and thus bring about or facilitate starting of the discharge. This starting arrangement has considerable fundamental importance as, other than contact starting by means of mechanically movable electrodes, it is the only arrangement that renders possible instantaneous starting of high pressure lamps in any state of operation at standard mains voltages without auxiliary electrodes and without additional external electric devices. However, up to the present it could be applied in practice only to low pressure discharge lamps and only to such types at very low voltages under 30 volts.

For perfect and reliable operation of the arrangement the starting wire or starting filament must have such dimensions that its resistance per unit length is at least equal to or greater than that of the discharge path after starting. As a consequence of this condition, the starting filament must be made of a rather thin wire that burns through instantaneously if the arc discharge starts from it even only for a short moment. The danger of burning through is considerably greater in high pressure lamps than in low pressure lamps because the high pressure arc forms a concentrated hot spot and has a much higher energy density in its starting point.

Several different means have been suggested to avoid that an arc starting point is formed and stays at the starting filament because one is aware of the fact that this can result in decreasing its life or eventually in burning it through quickly also in low pressure lamps. These measures e. g. consist in having the starting coil pass closely to the main electrodes so that they are preheated by the glowing filament or the arc already started at it. Thus the arc shall be influenced to jump over from the filament to the main electrode. According to another suggestion the starting coil is connected to the electrode leads not tightly but only loosely so that undefined contact resistances are formed that can favor the jumping of the arc from the filament to the main electrodes.

All these suggested arrangements have been found unreliable for use in high pressure lamps because they are based on the start of the arc at the filament and only aim to have the arc jump from the filament to the main electrodes later. It has been proven by extended experiments that in practice only such starting arrangements can be used in high pressure lamps that principally avoid starting of the arc at the filament. Thus no part of the starting filament acts as electrode during the starting procedure. The filament may be used exclusively as a means to create thermal electrons for the purpose of ionizing the main discharge path. It is the purpose of my invention to realize the above mentioned principle by several new arrangements or measures that can be used alone or simultaneously. Thus the known starting arrangement with incandescent parallel filament can be improved so that it also works reliably in high pressure lamps of all

2

kinds operating with solid incandescent electrodes at operating pressures higher than 0.5 atm. and at voltages higher than 100 v.

According to my invention the starting filament is not connected directly at both ends to the main electrode leads but only through certain solid resistors arranged inside or outside the discharge tube. As soon as a current flows through the starting filament after the mains voltage has been switched on, the voltage drops in the resistors result in the field strength along the filament being lower than that between the main electrodes before the arc has started. Thus the main discharge starts directly at the main electrodes and no intermediate arc starting point at the filament occurs. A certain minimum field strength difference is necessary to reach this result and its value depends greatly upon the details of the lamp design and the electric conditions. It can be necessary to reduce the voltage between the filament ends to less than one half or one third of the voltage on the main electrodes before starting of the arc. But in any case the resistors in series to the filament have to be so great that in each of them occurs a minimum voltage drop of at least 10% of the mains voltage or transformer voltage with which the lamp is operated.

The resistors can be manufactured by any method, e. g. as wire coils arranged in the spaces behind the main electrodes. But as there is very limited space behind the electrodes usually they will be made preferably of refractory materials with high resistivity as e. g. semiconducting refractory metal compounds. In the case of limited space within the discharge tube the ends of the starting filament can be led outside by special seals and can be connected outside through the resistors to the leads of the main electrodes. In this case the resistors will be in the bases or within the outer bulbs of the lamps preferably.

According to my invention another measure for preventing an arc starting spot on the filament or for transferring it safely and instantaneously to the main electrodes is the following: The electrodes have deep grooves or off-center holes parallel to the discharge axis and parallel to the starting filaments through which the ends of the starting filament are led. The starting filaments are fastened in such way that they are enclosed partly or completely by the electrode bodies but don't touch the electrodes. The starting filaments are electrically and mechanically connected only at the rear electrode ends or at the electrode leads, eventually through the above mentioned series resistors. In case the filaments are not stiff enough to avoid safely a contact to the electrodes, when the lamp is shaken, they can be equipped with a core of refractory insulating or poorly conducting material. Such cores can consist e. g. of sintered pure aluminum oxide, zirconium oxide, or thorium oxide.

Finally according to my invention the starting filaments are switched off the main electrodes immediately after the main arc has started for protecting them against burning through and securing the immediate transfer of the arc. For this purpose usually the ends of the starting filament must be led outside of the discharge tube by means of separate seals. As switches preferably one or two glow discharge—bimetal-relays, well known as "glow-starters," are used. In principle any kind of relay influenced by the lamp voltage or any manually operated switch can be used. In switching the starting filaments off the electrodes the additional advantage is won in that they consume no wattage during lamp operation and that consequently the operating efficiency of the lamp is not injured by the filaments.

The starting arrangements improved and rendered reliable according to my invention can be used in all kinds of high pressure lamps. They can have medium total

operating pressures from 0.5 to 5 or very high pressures up to 100 atm. or more. They can have activated or purely metallic solid incandescent electrodes and they can be filled with pure metal vapor, pure rare gas, or any combined mixture of metal vapors and rare gases.

The starting arrangement can consist of one or more starting filaments parallel to the discharge path. It can also be applied to lamps with more than one pair of electrodes or more than one arc.

The accompanying drawing shows two practical examples of high pressure lamps with starting arrangements according to my invention. Fig. 1 represents a spherical super high pressure lamp with rare gas filling of about 20 atm. suitable for operation on 110 v. D. C. or A. C. mains voltage. Fig. 2 represents a tubular high pressure mercury vapor lamp. In the Fig. 1 lamp, the rating is 2000 watt at an arc voltage of about 35 v. and an operating current of about 60 amps. Both relatively large electrodes E consist of pure tungsten and have off-center holes L parallel to their axis through which the ends of the starting filament Z extend freely without touching. The filament contains a core of sintered thorium oxide rod to attain the stiffness necessary to avoid electrical contact to the electrode. Behind the electrodes E the starting filament Z is connected to the electrode leads through both series resistors R₁ and R₂. R₁ and R₂ are 3 ohms each, the filament itself has a resistance of about 16 ohms. Thus, when the lamp is switched on, the current in the starting circuit is about 5 amps. and between the electrodes and the starting filament ends a voltage drop of 15 v. occurs. Thus the field strength between the front surfaces of the main electrodes is considerably greater than that between any parts of the starting filament. Besides this the resistance per unit length of the starting filament is considerably greater than that of the arc after starting. When the arc is started the voltage between the main electrodes drops to about 35 v., the current in the starting circuit decreases to about 1.5 amps. the latter being negligible compared to the arc current of about 60 amps.

Fig. 2 shows a mercury high pressure lamp of about 3 atm. operating pressure with tubular quartz bulb. It has 300 watts at about 120 v. arc voltage and 2.6 amps. operating current. The electrodes E have deep grooves N offset from the electrode axis and parallel thereto. Through these the starting filament is led freely without touching. The ends of the starting filament are led outside by means of separately sealed leads for the purpose of switching off after the starting of the main discharge. Outside of the discharge tube the two resistors R₁ and R₂ are in series to the starting filament, each having about 30 ohms resistance. The outer lamp circuit contains the choke-ballast D. The mains voltage Ne is 220 v. The starting filament has a resistance of 160 ohms. After switching the mains voltage on, a current of about 1 amp. flows in the starting circuit and both ends of the starting filament have a potential difference of about 30 v. each with respect to the adjoining main electrode. When the arc is formed the arc voltage or electrode voltage drops to about 120 v. and this decrease is used for switching off the starting circuit on both ends by means of both glow discharges bimetal relays ("glow-starter") G.

These glow-starters are of special three-electrode design and work as follows: When the mains Ne is switched on, the full mains voltage is between the outer lamp connections and between the movable bimetal electrodes 1 and the fixed counter electrodes 3 of the glow-starters. For this purpose the latter are connected to the opposite lamp connections by means of the relatively great auxiliary resistors H. A glow discharge is started in the glow starters, the current of which is limited by the resistors H. This current heats the bimetal electrodes 1, the same approach the electrodes 2 and make contact to them. By contact between 1 and 2 the starting circuit

is switched on, the filament Z starts glowing and the arc between the electrodes E starts. This results in a great drop of the electrode voltage, the glow discharge in the glow-starters cannot be maintained and extinguishes. The bimetal electrodes 1 open the contacts between 2 and 1, thus switching off the starting circuit on both ends. It is switched on again only after the mains voltage is connected again to the main electrodes after the arc has been extinguished. The electrodes in the glow-starters can be arranged so that the bimetal contact touches both electrodes 2 and 3 at the same time or shortly one after the other (first 2, then 3). The starting circuit is closed then only for the short moment between the extinguishing of the short-circuited glow discharge and the moment when the bimetal electrodes have cooled down enough to open the contact again. In this case the glow-starters operate automatically several times until an arc has started between the main electrodes of the lamps. If the starting circuit is to be switched off only on one end of the filament, this can be done by means of a simple two-electrode glow-starter.

Having thus disclosed my invention what I claim as new and desire to secure by Letters Patent of the United States is:

- 25 The combination which comprises an electric high-pressure gas-discharge lamp having an envelope with lamp electrodes spaced apart from one another within said envelope and adapted to have an arc discharge maintained in a path therebetween, and a starting arrangement comprising, a double-ended starting conductor within said envelope and paralleling and adjacent to said discharge path, first and second three-element glow starters positioned exteriorly of said envelope, each of said starters having a bi-metal first electrode, a second electrode and a third electrode, said starter electrodes being normally spaced from one another, a first resistor electrically connected between said bi-metal electrode of said first starter and said third electrode of said second starter, said bi-metal electrode of said first starter being directly electrically connected to one of said lamp electrodes, a second resistor electrically connected between said bi-metal electrode of said second starter and said third electrode of said first starter, said bi-metal electrode of said second starter being directly electrically connected to the other of said lamp electrodes, a third resistor electrically connected between said second electrode of said first starter and one end of said starting conductor, a fourth resistor electrically connected between said second electrode of said second starter and the other end of said starting conductor, each of said starters being adapted to maintain a glow discharge between their first and third electrodes upon application of an operating potential thereacross, each of said bi-metal electrodes upon receiving heat from said glow discharges being adapted to move into contacting relationship with the said second electrode of its respective starter to place a potential across said starting conductor to cause same to heat, the breakdown potential across said lamp electrodes being lowered by the heat of said starting conductor to cause said arc discharge to occur thereacross, said arc discharge being of sufficiently low resistance to extinguish the glow discharges in said starters to cause each of said bi-metal electrodes to cool, each of said bi-metal electrodes upon cooling being adapted to resume their normal spaced relationship, whereby said starting conductor is electrically isolated by said starters.
